(57) **CLAIM**

The ornamental design for a shish-kabob cooker, as shown and described.

DESCRIPTION

FIG. 1 is an exploded top, front and left side perspective view of a shish-kabob cooker showing my new design; FIG. 2 is an exploded left side elevational view thereof; FIG. 3 is an exploded right side elevational view thereof; FIG. 4 is an exploded front elevational view thereof; FIG. 5 is an exploded rear elevational view thereof; FIG. 6 is an exploded top plan view thereof; and, FIG. 7 is an exploded bottom plan view thereof. The electric cord shown broken away in FIGS. 2, 3, 6 and 7 is understood to represent indeterminate length.
